Attorney.

UNITED STATES PATENT OFFICE.

JOHN C. WACHA, OF PROVIDENCE, RHODE ISLAND, ASSIGNOR TO GEORGE H. CAHOONE COMPANY, A CORPORATION OF RHODE ISLAND.

CHAIN.

1,153,362.

Specification of Letters Patent. Patented Sept. 14, 1915.

Application filed May 17, 1915. Serial No. 28,527.

To all whom it may concern:

Be it known that I, JOHN C. WACHA, a citizen of the United States, residing at Providence, in the county of Providence and State of Rhode Island, have invented 5 certain new and useful Improvements in Chains, of which the following is a specification.

My invention relates to chains adapted 10 primarily for use in the jewelry art for bracelets, rings, watches and the like.

The essential objects of my invention are to avoid the use of solder; to afford longitudinal flexibility of the chain but prevent 15 lateral movement thereof; to insure such strength of connection of the units as to prevent breaking or loss of the latter; to provide a unit consisting of a single piece of material and which dispenses with the use 20 of independent connecting pins, screws, or rivets; to afford a maximum of space for the stone or ornamental surface; and to attain these ends in a structure inexpensive to manufacture, and wherein units may be 25 easily removed or substituted.

To the above ends essentially my invention consists in such parts and combinations of parts as fall within the scope of the appended claims.

90 In the accompanying drawings which form a part of this specification, Figures 1, 2, and 3 are plan, side, and bottom elevations of a series of my novel units assembled into a chain, Fig. 4 an enlarged longitudinal central section of a portion of the chain, Figs. 5, 6, and 7, a plan view, an end view, and a central sectional view of a unit before a stone is inserted, or the connections engaged, and Fig. 8, a side elevation of a 40 modified form of my chain.

Like reference characters indicate like parts throughout the views.

The chain comprises a plurality of novel units A adapted for interengagement. 45 Each unit consists of a substantially rectangular solid block, provided, if desired, in its upper face with a central conical cavity a, and having radial ribs a' extending to the cavity. The cavity is provided when a gem 50 B is to be employed as an ornament, in which case the ornament B extends into the cavity a, and by a suitable tool the material of the ribs a' is pushed over the edge of the gem to form retaining prongs as shown in 55 Fig. 1.

Each block A is provided at its rear end near the bottom with lugs C connected at the upper portions of their outer ends with a bar e, spaced from the body of the block, and above the plane of the bottom of the 60 body. The bottom of the body or block A is cut away to form a rectangular recess d which extends to a transversely disposed channel c near the bottom of the forward end of the body. A flat rectangular arm F, 65 integral with the forward end of the body, is bendable, downwardly directed, and of such length that when bent inwardly and upwardly it registers in the recess d. The thickness of the arm equals the depth of the 70 recess, so that after the arm is seated the bottom surface of the unit is flushed with the outer surface of the arm.

In assembling the described units, each 75 arm F is bent around an adjacent rod e, and the latter is loosely engaged in the bend f of the arm, and in the channel c whereby the adjacent units are pivotally connected, and the bodies are in contiguity at their lower 80 portions. It is important that the bodies be 85 very close together to produce the best appearance, but it is also necessary that the units pivot relatively to each other and be capable of assuming such positions as shown in Fig. 4. For this reason it is advantageous 90 but not essential, that the front and rear end faces of each unit body be inclined.

When an independent ornament is not employed the cavity a may be omitted and the top face of the member A be ornamented in 95 the flat or otherwise.

What I claim is:

1. A non-expansible chain comprising a plurality of units, each unit consisting of a body, lugs upon one end of the body, a bar 100 connecting the lugs, said body being provided with a transverse channel near its opposite end adapted to receive the bar of an adjacent unit, and an arm upon the first unit adjacent the channel flush with the body embracing said rod.

2. A non-expansible chain comprising a plurality of units, each unit consisting of a body, lugs upon one end of the body, a bar 105 integral with the lugs, said body being provided with a recess in its bottom face, a downwardly and rearwardly directed arm upon the other end of the body embracing the bar of the adjacent unit and having its free end seated in the recess. 110

3. A non-expansible chain comprising a plurality of units, each unit consisting of a body, lugs upon one end of the body, a bar connecting the lugs, said body being provided with a recess in its bottom face and with a transverse channel above the recess adapted to loosely receive the bar of an adjacent unit, and a bendable arm upon the body surrounding the channel with its free end seated in the recess flush with the face of the body.

In testimony whereof I have affixed my signature.

JOHN C. WACHA.
